HYDRAULIC PRESSURE DELIVERY DEVICE

Tony Rozanski and William Whitley,
Ramsey, N. J.

Application October 23, 1945, Serial No. 624,070

2 Claims. (Cl. 60—54.6)

1

This invention relates to hydraulically operated tools, and more particularly to a hydraulic pressure delivery device for supplying the tools with liquid under pressure for their operation, the primary object of the invention being to provide a simple and practical device of this character which can be constructed, operated and serviced at relatively low cost.

Another important object of the invention is to provide a device of the character indicated above which is particularly suited to being driven from power take-off devices of the types which are generally available.

With the foregoing and other objects and advantages in view, the invention consists of the novel construction and arrangement of parts hereinafter described and claimed.

In the accompanying drawing showing an illustrative embodiment of the invention:

Figure 1 is a side elevation, partly in longitudinal section, of a powered wood saw assembly.

Figure 2 is a vertical transverse section taken through the power take-off driven pressure producing assembly for operating the saw, and,

Figure 3 is a fragmentary top plan view of the saw assembly showing the same in relation to a log to be sawed.

Referring in detail to the drawing, wherein like numerals designate similar parts throughout, the saw assembly, generally designated A, comprises a forwardly elongated frame 1, comprising upper and lower longitudinal members 2 and 3, respectively, connected and spaced at their rear ends by a strut 4 and having a similar connecting member 5 adjacent their forward ends, acting as handholds. Another strut 6, connecting the forward ends of the longitudinal members 2 and 3 has pivoted thereon at 7 a pointed log impaling rod 8.

The lower longitudinal frame member 3 is in the form of a hydraulic cylinder closed at its forward end and having a hydraulic hose 9 connected to its rearward end, a shut-off valve having a trigger lever 10 being provided near the rear strut 4, so that the valve can be readily operated by a hand engaged with the strut 4.

A hydraulic piston 11 operates in the lower cylinder member 3 and has a piston rod 12 working through the forward end of the cylinder. The upper frame member 2 is formed with a bore 13 parallel to the piston rod 12, in which slides a guide rod 14 which works through the forward end of the bore 13. Fixed to the forward ends of the slideable guide rod 14 and piston rod 12 is a right angular saw holder bar 15, whose forward

side is slotted at 16 to receive the rear end of a straight saw 17, suitable saw securing means 18 being provided to hold the saw assembled with the holder bar. The holder bar depends below the saw frame 1 and has a lug 15' on its lower end to which is connected one end of a retracting spring 19 having its opposite end anchored to a lug 20 on the lower frame member 3, whereby the saw is normally retracted to a position in which the piston 11 is at the rearward end of the cylinder member 3, as shown in Figure 1.

The saw is operated by admitting fluid under pressure behind the piston 11 from the hose 9 by operating the valve lever 10 until the saw 17 has been projected forwardly from the starting position shown in Figure 1, whereupon the valve lever 10 is operated in the opposite direction to vent the fluid pressure behind the piston 11, through the vent port 21 provided at the rear end of the cylinder member 3, so that the spring 19 can retract the saw to the starting position. Repeated strokes of the saw are produced by repeating these operations as often as desired. As shown in Figures 1 and 3, the saw 17 is aided in its engagement with the log 22 or the like to be sawed, by impaling the impaling rod 8 in the log alongside of the path of movement of the saw.

The pressure producing assembly B comprises a hydraulic fluid containing casing 23 having a removable plate-like top 24, provided with two laterally spaced open cylinders 25 and 26, respectively, provided at their upper ends with hydraulic seals 27, 27 and opening at their lower ends into the casing 23. A working piston 28 is reciprocable in the cylinder 25 and a pressure-responsive piston 29 is reciprocable in the cylinder 26.

The pressure responsive piston 29 has a rigid piston rod 30 projecting upwardly therefrom and connected to the middle of a crosshead 31. Contractile springs 32, 32 are stretched between the ends of the crosshead on opposite sides of the piston rod 30 and the casing top 24, whereby the piston 29 is urged in a downward direction, but can yield upwardly whenever pressure within the casing 23 exceeds the combined strength of the springs 32, 32.

For working the piston 28 a connecting rod 33 is provided which is pivotally connected to the piston at 34 and is journalled at 35 on a crank throw 36 on a crankshaft 37 which is journalled in the upper ends of standards 38, 38 which rise at and are connected at 39 with the opposite ends of the casing 23.

One end of the crankshaft 37 has a gearwheel 40 which is in mesh with a pinion 41 on a stub-

shaft 42 mounted at 43 on the related standard 38, to which pinion 41 is adapted to be operatively connected any suitable available power take-off, as here represented by in part by the shaft 44.

It is obvious that as the pinion 41 is turned by operation of the power take-off, the gearwheel 40 and hence the crankshaft 37 will be turned, thereby reciprocating the piston 28. On the downward stroke of the piston 28 the hydraulic fluid (not shown) in the casing 23 will be compressed and pass out through the hose 9 to the saw assembly A, so as to supply the same with fluid pressure for its operation. The piston 29 normally depends within the casing 23, is shown in Figure 2, due to the action of the springs 32, 32, thereby occupying a corresponding amount of cubic space therein. However, as pressure is built up in the casing by the operation of the piston 28, beyond the holding strength of the springs 32, 32 the piston 29 will rise against the resistance of the springs, thereby to a corresponding extent relieving the pressure within the casing. By properly choosing the components involved, including the springs, the piston 29 may be made to serve to relieve any expected excess pressure in the casing 23 in the manner indicated, and at the same time serve as a visual indicator of any unusual rise in such pressure, since an unusual rise of the cross head 31 above the casing top 24 is readily perceptible.

Having thus described our invention what we claim as new and desire to secure by Letters Patent is:

1. A hydraulic pressure delivery device comprising a hydraulic fluid containing casing having a closed top, a first open ended cylinder fixedly supported in said closed top and having one end in communication with the interior of said casing and having the other end projecting beyond said closed top, a first piston mounted in said cylinder for reciprocatory movement and having one end adjacent said one end of said cylinder and having the other end extending beyond said other end of said cylinder, a rotatable crankshaft having a crank throw intermediate its ends arranged exteriorly of and supported on said casing, a connecting rod having one end connected to the other end of said piston and having the other end connected to said crank throw, a second open ended cylinder spaced from said first cylinder and fixedly supported in said closed top and having one end in communication with the interior of said casing and having the other end projecting beyond said closed top, a second piston mounted in said second cylinder for reciprocatory movement and having one end adjacent said one end of the latter named cylinder and having the other end extending beyond said other end of said second cylinder, means resiliently connecting said second piston to said closed top casing, an outlet connected to said casing for conveying fluid under pressure from said casing, and means connected to said crankshaft for effecting the rotation of the latter to thereby cause reciprocation of said first named piston to exert pressure on the fluid in said casing and force said liquid under pressure out of said outlet.

2. A hydraulic pressure delivery device comprising a hydraulic fluid containing casing having a closed top, a first open ended cylinder fixedly supported in said closed top and having one end in communication with the interior of said casing and having the other end projecting beyond said closed top, a first piston mounted in said cylinder for reciprocatory movement and having one end adjacent said one end of said cylinder and having the other end extending beyond said other end of said cylinder, a rotatable crankshaft having a crank throw intermediate its ends arranged exteriorly of and supported on said casing, a connecting rod having one end connected to the other end of said piston and having the other end connected to said crank throw, a second open ended cylinder spaced from said first cylinder and fixedly supported in said closed top and having one end in communication with the interior of said casing and having the other end projecting beyond said closed top, a second piston mounted in said second cylinder for reciprocatory movement and having one end adjacent said one end of the latter named cylinder and having the other end extending beyond said other end of said second cylinder, a cross-head arranged adjacent to and spaced from said other end of said second piston and secured to the latter, resilient means operatively connected to said crosshead and said closed casing top for urging said second piston into the interior of said casing, an outlet connected to said casing for conveying fluid under pressure from said casing, and means connected to said crankshaft for effecting the rotation of the latter to thereby cause reciprocation of said first named piston to exert pressure on the fluid in said casing and force said liquid under pressure out of said outlet.
